PRINTING MACHINE

Emil L. Mueller, Rutherford, N. J.

Application July 28, 1933, Serial No. 682,541

10 Claims. (Cl. 101—269)

This invention relates to a printing machine of the general type disclosed in my pending application Serial No. 564,377, filed September 22nd, 1931, being in the nature of an improvement upon the structure shown in said pending application, and the machine being adapted for the quick and convenient printing of relatively few copies from a given electro-type or the like, the electro-type being readily removed so that it may be replaced by another from which copies are desired.

An object of the present invention is to provide a machine which will be highly efficient, accurate and practical in the printing of copies from the type bed.

A further object is to so construct the machine that it will include parts conducive to the securing of great accuracy in the placement of printed impressions on paper sheets.

A more detailed object is to construct the sheet receiving and holding means on the printing roll employed so as to include parts to facilitate the accurate placement and retention of paper sheets on the printing roll.

A further detailed object is to provide a sheet stop directly on the printing roll disposed as a rest against which sheets may be placed in feeding the sheets to the roll, and to provide means to protect against injury of said stop during rotation of the printing roll.

A further detailed object is to provide a sheet gripper and to provide for movement of said gripper into sheet gripping position while the printing roll stands idle for receiving a sheet being fed to said gripper.

A further detailed object is to provide drive means for the printing roll including parts affording a period of lost motion as between the drive means and the printing roll, together with sheet gripper means connected to be operated during said period of lost motion.

A further detailed object is to provide a cam movable into and out of operative position with respect to the sheet gripper and to provide lost motion driving connections for the printing roll operable to move the cam from one position to another to thereby insure movement of the sheet gripper to sheet gripping position without accompanying movement of the printing roll.

A further object is to provide stop means for the printing roll mechanism of a character to permit variation in the precise point of stoppage of travel of the printing roll mechanism.

A further object is to provide means insuring that the printing roll will be held locked in im-

pression position during travel of the printing roll mechanism over the printing type.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:

Fig. 1 is a side elevational view of a printing machine constructed in accordance with this invention.

Fig. 2 is a top plan view of the structure seen in Fig. 1.

Fig. 3 is an enlarged detail view, partly in vertical section, showing the construction and operation of the sheet gripper means in receiving and gripping a paper sheet from the paper sheet feeding table.

Fig. 4 is a top plan view of the structure appearing in Fig. 3.

Fig. 5 is an enlarged detail sectional view of the sheet stop device employed upon the printing roll, being on the plane of line V—V of Fig. 6.

Fig. 6 is an elevational view of the structure illustrated in Fig. 5.

Fig. 7 is a diagrammatic view illustrating the manner of operating the sheet gripper device in releasing a sheet, said figure containing also a diagrammatic view of wiring and switches which may be employed, and also the manner of locking the printing roll in impression position.

Fig. 8 is an enlarged detail sectional view illustrating the lost-motion device employed, and

Fig. 9 is a similar sectional view illustrating the construction of slippage clutch employed.

Referring now to the drawings forming part hereof for describing in detail the embodiment of the invention illustrated therein, the reference character L indicates a main frame preferably including legs as 1—1 by which the main bed or table portion 2 is elevated at a suitable height from the floor.

The bed 2 is of a general rectangular shape and has opposite rack bars as 3—3 extending along its longitudinal margins.

The reference character G indicates generally the printing roll mechanism.

The reference character H indicates a suitable inking roller mechanism which is movable along

the bed, being connected with the printing roll mechanism substantially as heretofore.

The reference character A indicates generally the paper sheet feed table. This is arranged in a stationary position at one end of the table 2 substantially as illustrated, being carried upon one or more standards as 4 which rise from the table 2 and which carry at their upper ends a vertically adjustable inclined table plate 5 upon which may rest a pile of paper sheets 6 in the usual way.

The plate 5 has its inclined portion as 7 disposed so that the sheets may be moved by hand downwardly therealong, as indicated at 8, Fig. 3, and into engagement with the printing roll one after the other as will be presently described.

The printing roll mechanism G and the inking roller mechanism H are mounted to travel back and forth along the length of the table, the printing roll mechanism having carrying rollers or wheels as 9—9 at its opposite sides for travelling upon tracks 10 which are provided at the opposite sides of the table 2 to receive them, and the inking roller mechanism having similar rollers 11 or wheels as 11 for likewise engaging the tracks 10, all as heretofore.

The mechanisms G and H are formed preferably separate from each other so that they may be capable of movement back and forth as independent elements whenever desired. A latch as 12 may be employed for detachably connecting the mechanisms G and H as heretofore.

The printing roll mechanism G includes the opposite side frame members 13—13 suitably connected and carrying a reversible electric motor 14 as heretofore.

Upon the shaft 15 of the motor is carried a slippage clutch mechanism including a disc 16 fixed rigidly to said shaft, a sprocket wheel 17 freely rotatable upon the shaft and having opposite friction disc portions 18—18 fixed thereto also freely rotatable upon the shaft, a friction disc 19 longitudinally movable along the shaft but held against rotation as by a feather and slot connection indicated at 20, and a compression spring 21 bearing at its outer end against a nut secured on the shaft and having its inner end pressing against the disc 19 and thereby frictionally clamping the sprocket wheel and disc portions 18—18 between said disc 19 and the disc 16 with sufficient frictional grip to insure rotation of the sprocket 17 normally with the shaft 15 but permitting slippage as between the sprocket and said shaft whenever such slippage is desirable as for instance when for any reason rotation of the sprocket is suddenly arrested.

From the sprocket 17 a sprocket chain 22 extends about a second sprocket 23 which is carried by a short shaft 24.

The shaft 24 has a pinion 25 thereon meshing with a gear 26 fixed to a cross shaft 27.

The sprocket 23 is connected with the pinion 25 by means of a lost motion device which consists of a disc 28 fixed to the pinion 25, said disc and pinion being freely rotatable as one unit upon the shaft 24. The disc 28 is formed with an arcuate slot 29 therein within which engages a pin 30 fixed rigidly with the sprocket 23, the arrangement thereby providing that upon any reversal of direction of rotation of the sprocket 23, and hence of travel of the pin 30, such reversal will not be transmitted to the pinion 25 and shaft 27 until the sprocket 23 has first rotated sufficiently to carry the pin 30 to the opposite end 75 of the slot 29. In the instance illustrated the

slot 29 is shown of such arcuate length as to permit substantially a one-third rotation of the sprocket 23 before motion is imparted to the pinion 25 and shaft 27.

Fixed to the sprocket 23 so as to at all times 5 rotate as one therewith is a pinion 31 in constant mesh with a gear 32 on a stud shaft 33. Fixed to move with the gear 32 is a cam 34 against which bears the lower end of a crank lever 35, there being a suitable anti-friction roller as 36 10 provided upon the lever for engaging the cam.

The lever 35 is pivotally mounted as at 37 upon the adjacent frame piece 13 and at its upper end has fixed thereto a link as 38 connected as at 39 for sliding a slidably mounted cam as 40, the purpose of which will be presently fully set forth. A tension spring as 41 is arranged for urging the lever 35 against the cam 34 and for incidentally urging the cam 40 toward what may be referred to as its inoperative position as shown 20 by dotted lines in Fig. 3.

The shaft 27 extends entirely across the machine, being mounted in the opposite side frames 13—13, and fixed to said shaft spaced apart thereon are two gear wheels as 42 and 43 the 25 teeth of which intermesh constantly with the teeth of the rack bars 3—3 respectively so that rotation of the gears 42 and 43 will cause the printing roll mechanism to move bodily along the length of the rack bars from adjacent one end 30 of the table to adjacent the opposite end, in either direction according to the direction of rotation of the motor sprocket 17.

As an example of means for reversing the direction of rotation of the motor sprocket 17 the 35 drawing herewith, Fig. 7, illustrates diagrammatically suitable reversing switches as 44, 45 and 46 arranged in the motor circuit represented by wires 47 and 48 which extend from mains 49 and 50.

The switches 44 and 45 may be mounted upon the frame of the machine adjacent opposite ends respectively and may have their control arms as 51 and 52 standing in the path of operating members 53 and 54 carried by the printing roll mechanism G so that one of said switches will be thrown to reverse the motor each time the printing roll mechanism reaches an end of the table.

The switch 46 may be mounted at a convenient location for momentary control by an operator 50 at any time.

A circuit breaking switch as 55 may be provided in the circuit, also at a convenient location for instant control by the operator whenever occasion requires.

It will be seen that the switch devices and wiring illustrated are such that as the printing mechanism reaches the paper sheet feed table A and operates the switch 45 the motor will be thereby reversed and will, after first moving the pin 30 60 to the opposite end of slot 29, begin to propel the printing mechanism away from the table A. Also that as the printing mechanism reaches the opposite end of the machine and operates the switch 44 the motor will be thereby again reversed and 65 will, after first moving the pin 30 backward to the first end of the slot 29, begin to propel the printing mechanism again toward the table A, this operation continuing as often as desired by the operator and being subject to discontinuance by operation of switch 55 which the operator is at liberty to employ for breaking the circuit at any moment or as often as he chooses.

Because of the lost motion mechanism includ- 75

ing pin 30 and slot 29 the shaft 27 and gears 42 and 43 will stand motionless, and the printing roll mechanism will remain at rest, after reaching its appointed position beneath the paper sheet 5 feed table A, for an appreciable period before beginning return travel toward the opposite end of the bed.

Of course the same period of rest of the printing roll mechanism will occur at the opposite end of 10 the bed but this is relatively immaterial.

A suitable electro-type or the like as 56 may be mounted upon the surface of the bed 2, being held by appropriate means such for instance as the clamp parts 57 and 58 as more fully set forth 15 in the mentioned co-pending application.

The printing roll comprised in the printing roll mechanism is indicated generally by the reference character 59 and is provided with end gears 60 and 61 which mesh with the rack bars 3 so as to 20 insure rotation of the printing roll in opposite directions as said roll moves back and forth along the bed in the usual manner.

A set of gripper fingers as 62 is carried by the printing roll, being mounted spaced apart along 25 the length of a rock shaft 63 which is arranged within a suitable cavity 64 of the roll in the usual manner. The opposite ends of the shaft 63 are rotatably received in bearings provided through the opposite end walls 65 and 66 of the printing 30 roll.

At one of its ends the shaft 63 projects beyond the end wall 65 and carries a laterally extending arm 67 fitted with an anti-friction roller 68 for engaging the cam 40 heretofore mentioned. A 35 spring device 69 is connected with the arm 67 operating to always urge the shaft in a direction to hold the gripper fingers normally in gripping position against the outer edge surface 70 of a clamp bar 71 carried by the printing roll.

The timed relationship of the mechanism 34—39 heretofore mentioned, for operating the cam 40, to the rotative position of the printing roll on the rack bars 3—3, is such that as the printing roll approaches the paper sheet feed table A the cam 40 will at that time have been moved by the cam 34 to the position in which it is shown in full lines in Fig. 3 so that just as the printing roll moves through its last fraction of rotation before 45 coming to rest beneath the table A the anti-friction roller 68 connected with the gripper fingers will strike the under surface 72 of the cam 40 and ride along the surface 73 of said cam 40 and come to rest with the gripper fingers held open, all as substantially shown in full lines in Fig. 3, 50 the motor 14 having been stopped by engagement of the operating member 54 with the switch control arm 52.

It is intended that in the period while the printing roll stands at rest beneath the table A, with the gripper fingers open, the operator shall slide a sheet of paper, as shown as 8 in Fig. 3, downwardly along the surface 7 of table A and into position for being gripped by the gripper fingers on the printing roll, and that the gripper fingers shall actually grip and hold said sheet in fixed 55 relation to the printing roll before said roll shall begin its return travel for printing the sheet.

To this end it will be noted that reversal of the 60 motor 14, following the movement of switch arm 52 and rotating the sprocket 23 without accompanying movement of shaft 27 until the pin 30 reaches the opposite end wall of the slot 29, but with the gear 32 and cam 34 meanwhile rotating, 65 will cause the cam 34, in this interim, to rotate

sufficiently to, first, provide a movement of its substantially concentric surface portion 74 with respect to roller 36 to hold the cam 40 motionless and the gripper fingers open while the sheet 8 is being introduced, and, second, to thereafter permit roller 36, under the strain of spring 41 to travel along the cam surface portion 75 so that the cam 40 will be slid away from the roller 68 of the gripper fingers thereby allowing the gripper fingers, without rotation of the printing roll, to 10 be moved into gripping engagement with the sheet under the impulse of spring 69.

The cam 34 is so positioned and designed with respect to the slot and pin lost-motion connection that the pin will engage the opposite end of the 15 slot and thereby begin return rotation of the printing roll away from the table A just after the gripper fingers have come to rest in gripping contact against the paper sheet.

One or more stops 76 are carried by the printing roll 59 in position to receive the lower edge 20 of the paper sheet 8 thereagainst. These stops constitute rests against which the lower edge of the sheet may be brought by the operator in sliding the sheet downwardly along the table A onto 25 the printing roll, and they thus positively and accurately locate the sheet on the printing roll preparatory to gripping of the sheet by the gripper fingers.

These stops are mounted at spaced points along 30 the length of the clamp bar 71 and, as shown in detail in Figs. 5 and 6, they are pivotally connected with the clamp bar as by a pivot pin 77 which is received within a slot 78 in such wise that although the outer ends of the stops normally project beyond the printing surface 79 of the printing roll yet they are yieldable substantially radially of the printing roll to avoid breakage or other undesirable results in the event that they should come into contact with any object resting 35 on the surface of the bed 2 during the travel of the printing roll along said bed.

Light springs as 80—80 are carried by the clamp bar in engagement with the pivot rod 77 always urging the stops radially outwardly of the printing 45 roll but permitting radial inward movement of said stops at any time.

A threaded stud 81 has a nut as 82 adjustable thereon in engagement with the stop for adjusting the position of the sheet stopping surface 83 50 of the stop in a direction circumferentially of the printing roll, a light compression spring 84 urging the stop about its pivot 77 in one direction and the nut 82 serving to adjustably move the stop against said spring circumferentially of the roll. 55

Adjacent each of the stops 76 is a sheet guiding arm 85 carried by and fixed to a cross bar 86 oscillatably mounted in the opposite side frame members 13—13 of the printing roll mechanism. These guide arms are preferably received in upwardly facing notches 87 provided for the purpose at the upper ends of the stop members 76 and when resting in said notches they provide downwardly curving inclined surfaces 88 leading to the sheet stopping surfaces 83 along which the 60 lower edge of the sheet 8 may be guided to said surfaces 83 in the period while the operator is sliding the sheet 8 to position against the stop surfaces 83.

A laterally extending arm 89 is fixed to the cross 65 bar 86 and has connected therewith a tension spring 90 constantly urging the arms 85 downwardly toward the surface of the printing roll.

A second laterally extending arm 91 is fixed to the cross bar 86 and carries an anti-friction roller 75

92 bearing constantly against the surface of the printing roll at one end of the roll as for instance against the outer peripheral surface of the end wall 66 of the printing roll. This peripheral surface portion of the printing roll is formed with a small cam groove 93 therein adapted to receive the anti-friction roller 92 as the printing roll rotates beneath said roller, said cam groove 93 being positioned at an appropriate radial location 5 to permit and cause the guide arms 85—85 to stand for an appropriate period in their lower positions within the notches 87 during the time while the printing roll stands motionless adjacent the table A for receiving a paper sheet from said 10 table. The cam groove permits the arms to fall into the notches 87 as the printing roll approaches its position of rest beneath the table A, permits them to stand in guiding position within said notches during the entire period while the printing roll is motionless beneath said table A, and causes them to be lifted again out of the notches and free of the printing roll, as indicated by dotted lines in Fig. 3, as the roll begins to travel on its 15 return toward the opposite end of the machine.

25 The clamp bar 71 is formed separate from the printing roll and is carried detachably by said roll. Its lower longitudinal edge portion is received within a groove 94 provided in the printing roll and its opposite end portions are received 20 within approximately radially disposed grooves 95—95 formed in the inner surface of the opposite end walls 65, 66 of the printing roll, the clamp bar being thereby removable by being slid approximately radially out of the grooves 95—95 25 but being firmly supported as a part of the printing roll structure when in position within the grooves 94 and 95.

In order to insure against accidental outward sliding movement of the clamp bar suitable spring gripping devices as shown at 96, in Fig. 4, may be arranged to be co-operative between the end walls 65 and 66 and the adjacent end portions of the clamp bar. In the instance illustrated the gripping devices 96 each consists of a ball 97 spring 40 pressed into a shallow seat 98 in the end surface 45 of the bar.

The purpose of making the clamp bar separate and detachable from the remainder of the printing roll is multifold, and among the different results obtained may be mentioned:

First, that it provides a convenient and practical carrier for the stop members 76 permitting their easy assembly in the structure, their convenient repair and removal whenever necessary, 50 and the substitution of different clamp bars having differently positioned stops 76 thereon whenever occasion requires.

Second, that it provides an accurately placed metallic surface portion, as 70, with respect to the 60 stopping surfaces 83 of the stop members 76, and with respect to which said stopping surfaces may be accurately adjusted as occasion demands, and

Third, that it provides, by removal of the clamp bar, easy access to the retaining device as 99 by 65 which one end portion of the paper band or pad member 100 is fixed to the printing roll, as illustrated in Fig. 3.

When a paper sheet from the table A has been set by the operator against the stops 76 and the 70 gripper fingers have gripped upon the edge of said sheet, pin 30 having by this time travelled to the lower end of the slot 28, Fig. 1, then the return travel of the printing mechanism begins. The cam groove 93 lifts the arms 85 and the 75 printing mechanism progresses on its way toward

the opposite end of the machine carrying the paper sheet with it in such manner that the sheet will be applied against the electro-type 56 and be printed as will be readily understood.

As the printing mechanism approaches the end 5 of the machine away from the table A, the paper sheet having been now printed and being ready for removal, the gripper fingers are moved open to release the sheet by mechanism such as that illustrated in Fig. 7 and more fully shown and 10 described in said co-pending application, or by other means suitable to the purpose.

The mechanism illustrated in Fig. 7 consists of an arm 101 which is fixed to one end of the rock shaft 63 carrying the gripper fingers. The end 15 of this arm carries an anti-friction roller 102 which rides against a cam strip 103 by which it is made to swing the gripper fingers open as the printing mechanism comes to rest so that the printed sheet stands free for removal by the 20 operator. The cam strip 103 is moved into and out of its operative position by being connected with one arm as 104 of a bell crank lever the 25 opposite arm as 105 of said lever being connected by a link 106 with the movable bearing member 107 of the printing roll, said bearing member 107 being connected as by a link 108 with one arm as 109 of a second bell crank lever the other arm as 110 of which is disposed for engaging an abutment 111 fixed upon the frame of the machine. 30 The arrangement is such that, as the printing roll mechanism travels, the bell crank 109—110 will be swung to rotate the bearing member 107 and thereby swing the bell crank 104—105 and lift the cam strip 103 so that a notch as 112 of 35 said strip will move free of a pin 113 thereby forcing the cam strip to swing toward the pivotal axis of the printing roll and hence into operative position effective to produce a sufficient swinging movement of the arm 101 to release the 40 gripper fingers.

It will be understood that the switch operating member 53 will engage the control arm 51 at switch 44 to reverse or stop the motor 14 just 45 prior to this moment.

The movable bearings 107 of the printing roll are for the purpose of lifting the printing roll out of impression position or for lowering it into impression position in the same manner as more 50 fully illustrated and described in said co-pending application, the members 107 being rotatably mounted in the side frame members 13—13 and carrying the pivot shaft, as 114 of the printing roll eccentrically therein so that the printing roll 55 will be elevated or lowered according to the rotative direction of movement of the members 107.

With respect to the illustration Figs. 1 and 7 it is noted that a slight rotary movement of the member 107 in a contra-clockwise direction, such as is imparted thereto when the arm 110 strikes the abutment 111, operates to lift the printing roll out of impression position so that thus the printing roll will have no contact with the electro-type 56 during the return travel of the printing 60 roll mechanism to position beneath the paper sheet feed table A.

It is noted further that a slight rotary movement of the member 107 in a clock-wise direction, such as will be imparted to the member 107 70 when the arm 110 strikes the abutment as 115 when the printing roll mechanism reaches its position beneath table A, will operate to lower the printing roll again to impression position so that now the printing roll will have a proper 75

printing contact with the electro-type during travel of the printing roll mechanism away from the table A.

Experience has shown that it is desirable not only to insure great accuracy of placement of the printing roll when lowered to its operative or impression position but also to provide a positive locking means against any vertical displacement, however slight, of the printing roll during the printing operation.

To this end the present invention proposes that the link 108 and the bell crank arm 109 shall be so proportioned and disposed as to constitute a toggle capable of movement into and slightly beyond a dead center position, as clearly illustrated by dotted lines in Fig. 7, when the arm 110 engages the abutment 115. A suitable stop 116 is provided upon the adjacent side frame member 13 to limit movement of the toggle in its dotted line or locked position and thus defines with great accuracy the rotative position of member 107, and hence the vertical position of the printing roll, following each engagement of the arm 110 with abutment 115. No ordinary amount of upward pressure against the printing roll, as during printing, being capable of disturbing the locked toggle.

This invention further provides means to insure a properly locking operation of the toggle 108-109 incident to every visit of the printing roll mechanism to the table A and regardless of certain irregularities of position of the printing roll mechanism on different visits.

In the illustration herewith the abutment 115 is shown as being resilient. It consists of a striker plate 117 carried by one or more supporting rods 118 horizontally slidably mounted in a base member 119 and held yieldably away from the base member by a suitable spring or springs 40 as 120.

Assuming the toggle 108-109 to be in broken position as shown by full lines in Figs. 1 and 7 and the printing mechanism to be travelling toward the right Fig. 1: As soon as the anti-friction roller 121 at the lower end of the arm 110 strikes the plate 117 the force of the blow, considered together with the amount of work which must be performed in moving the toggle from its fully broken position against a stop 122 to near its dead center position, will cause the spring or springs 120 to yield until either the striker plate engages the opposing surface of the base member 119 or the power of the spring 120 becomes sufficiently great to initially move the toggle out of its broken position. Continued movement of the printing roll mechanism will cause the toggle to move to, or near to, a dead center position, and it is intended that the power of spring 120 will at this moment operate to move the toggle, through and beyond its dead center position to its locked position against the stop 116.

Owing to the fact that the stoppage of travel of the printing roll mechanism is due primarily to the shutting off, or reversal, of the motor 14, the precise point along the length of the bed 2 at which the printing roll mechanism will actually come to rest beneath the table A will vary within appreciable limits in different visits, this due to numerous causes as for instance differences in the power of the motor current at different moments, and the differences in the amount of friction encountered from time to time in the travel of the printing roll mechanism.

The operation of the spring 120 in moving the

toggle through dead center position as above described will be performed with equal efficiency irrespective of the precise position at which the printing roll mechanism comes to rest beneath table A.

If the printing roll mechanism moves relatively far beneath the table 5, the springs 120 will move the toggle through dead center a little early and the then distended springs 120 will be in condition to permit return of the striker plate 117 10 toward the base member enough to permit the required further travel of the printing roll mechanism before the point of rest is reached.

While if the printing roll mechanism moves relatively less far beneath the table, the springs 15 120 will move the toggle through dead center at a moment nearer to the actual moment when the printing roll mechanism comes to rest, the springs 120 operating to snap the toggle through dead center but there being little or no continued 20 travel of the printing roll mechanism to thereafter move the striker plate toward the base member 119.

The entire mechanism as herein shown and described is of a highly precise and accurate operation thoroughly efficient for performing its various functions and for enabling the accurate registry of paper sheets on the printing roll so that printed characters requiring to register with each other in subsequent printing operations on a given 30 paper sheet may be made to register with perfect accuracy and without any great amount of adjustment or care by the operator. The operator is required simply to place one edge of his paper sheet against the adjustable guide stop 123 on 35 the table A and slide it downwardly against the stop surface 83 of stop 76 on the printing roll, and leave the rest to the machine.

The guide stop 123 is adjustable in a direction transversely of the printing table and it may be 40 mounted in any approved way as for instance by having a slot as 124 therein through which a pair of adjustable clamping screws as 125 extend into engagement with any selected pair of a row of 45 threaded apertures 126 provided in the plate or 50 table portion 5.

Mounted upon a suitable cross rod 127 carried by the table 5 is provided one or more retaining devices as 128-128 in the form of brushes the bristles of which are adapted to rest lightly upon 55 the upper surface of the paper sheet for holding the sheet against accidental retrogressive movement at all times.

Upon a second cross rod as 129 carried by the 55 table 5 is a pointer 130 freely adjustable transversely of the machine, the rod 129 having scale indications thereon as at 131 from which may be read the position of the pointer lengthwise of the rod.

Upon the upper surface of the bed 2 there is 60 provided similar scale indications as at 132.

The operator may utilize the pointer 130 and the scales 131 and 132 to facilitate the proper placement of the paper sheet 8 on table A with 65 respect to the electro-type 56. By setting the pointer 130 for instance at a point on scale 131 corresponding with the reading on scale 132 marking the edge of a paper sheet properly laid upon the electro-type 56 and then adjusting the guide 70 stop 123 at a location to properly guide the sheet, as indicated in Fig. 2, the sheet will be thereby guided onto the printing roll at a proper location lengthwise of the printing roll to suit the position 75 of the electro-type. When not in use the pointer

130 may be slid to an out-of-the-way position at either end of its supporting rod 129.

Adjustment of the exact position of the cam 40 with respect to the lever 35 may be provided for in 5 any desired manner but in the instance illustrated it is suggested that the upper end portion of the lever 35 may have a separate extension part as 133 adjustably pivotally connected with the main portion of the lever by a clamp screw as 134 whereby 10 the part 133 may be held substantially rigid in any desired rotative relationship upon the pivot formed by the clamp screw as will be readily understood.

The yieldable stop 115 not only serves to operate the toggle for locking the toggle as above described but constitutes also a stop means effective to define the point of stoppage of the printing roll mechanism adjacent the table A. Being yieldable, it will not always effect a stop- 20 page of the printing roll mechanism at the same identical point at each visit of the printing roll mechanism, but will permit a variation of the point of stoppage, it being noted in this connection that when the power of springs com- 25 prised in the yieldable stop begins to be felt by the travelling printing roll mechanism then the slippage clutch on the motor shaft will become operative and will in some instances permit actual stoppage of the printing roll mechanism with 30 the springs of the yieldable stop more or less distended, without necessity for complete stoppage of the motor, and in other instances the yieldable portion of the stop may be pressed firmly against the base of the stop at this time, 35 according principally to the speed, or momentum, of movement of the printing roll mechanism at the moment when the motor is deprived of its propelling current.

As many changes could be made in this construction without departing from the scope of the invention as defined in the following claims, it is intended that all matter contained in the above description, or shown in the accompanying drawings, shall be interpreted as illustrative only 45 and not in a limiting sense.

Having thus described my invention, what I claim as new and desire to secure by Letters Patent is:-

1. In a printing machine, the combination with 50 a printing roll of a printing roll carriage mounted to travel back and forth between two positions along a suitable bed and having bed engag- 55 ing means effective to cause rotation of said roll in opposite directions during the back and forth travel of said roll, a motor mounted on said carriage and driving connections between the motor and the roll and a reversing switch for the motor to cause the roll to travel back and forth along the bed, of means comprised in said 60 driving connections providing a period of rest for said roll following the beginning of operation of the motor to move the roll in at least one direction along the bed.

2. In a printing machine, the combination with 65 a printing roll of a printing roll carriage mounted to travel back and forth between two positions along a suitable bed and having bed engag- 70 ing means effective to cause rotation of said roll in opposite directions during the back and forth travel of said roll, a motor mounted on said carriage, and driving connections between the motor and the roll and a reversing switch for the motor to cause the roll to travel back and forth along the bed, of means comprised in said 75 driving connections providing a period of rest

for said roll following the beginning of operation of the motor to move the roll in at least one direction along the bed, and means associated with said connections and operable thereby to grip a paper sheet upon the roll during said 5 period of rest.

3. In a printing machine, a printing roll, a carriage therefor, a sheet gripper finger carried by said roll, a motor mounted on said carriage, connections between the motor and the roll to 10 cause rotation of the roll and progress of the carriage by operation of the motor, means comprised in said connections providing a period of rest for the roll, and means effective to operate the gripper finger by power of the motor during 15 said period of rest.

4. In a printing machine, a table, a printing roll mechanism and a carriage therefor mounted to travel back and forth along said table, a motor mounted on said carriage and driving connec- 20 tions between said motor and roll including a lost motion connection to provide a period of dwell, a reversing switch for said motor, said printing roll mechanism including a movable sheet gripper, and means to operate said sheet 25 gripper during said period of dwell.

5. In a printing machine, a table, a printing roll and a carriage therefor mounted to roll back and forth along said table, a motor mounted on said carriage and driving connections between 30 said motor and roll including a lost motion connection to provide a period of dwell, a reversing switch for said motor, a sheet gripper carried by said roll, and means to operate said sheet gripper during said period of dwell. 35

6. In a printing machine, a table, a printing roll and a carriage therefor mounted to roll back and forth along said table, a motor mounted on said carriage and driving connections between 40 said motor and roll including a lost motion connection to provide a period of dwell, a reversing switch for said motor, a sheet gripper carried by said roll, and means by which said motor is operable to operate said sheet gripper during said period of dwell. 45

7. In a printing machine, a table, a carriage mounted to travel back and forth along said table, a printing roll carried by said carriage, a motor mounted on said carriage, a sheet gripper carried by said roll, driving means for said carriage 50 by said motor including a lost motion connection providing a period of dwell for said carriage, a reversing switch for said motor and means whereby to operate said sheet gripper by said driving means during said period of dwell. 55

8. In a printing machine, a table, a carriage mounted to travel back and forth along said table, a printing roll carried by said carriage, a motor mounted on said carriage, a sheet gripper carried by said roll, driving means for said 60 carriage by said motor including a lost motion device providing a period of dwell for said carriage, a reversing switch for said motor and means whereby to operate said sheet gripper by said driving means incident to functioning 65 of said lost motion device.

9. In a printing machine, a table, a carriage mounted to travel back and forth along said table, a printing roll carried by said carriage, a motor mounted on said carriage, a sheet gripper carried by said roll, driving means for said carriage by said motor, including a lost motion device providing a period of dwell for said carriage at one extreme of travel of said carriage, a reversing switch for said motor and means 75

whereby to operate said sheet gripper by said driving means during said period of dwell.

10. In a printing machine, a table, a carriage mounted to travel back and forth along said table, a printing roll carried by said carriage, a motor mounted on said carriage, a sheet gripper carried by said roll, driving means for said carriage by said motor including a lost motion de-

vice providing a period of dwell for said carriage incident to the reversal of travel of the carriage, a reversing switch for said motor, and means whereby to operate said sheet gripper by said driving means incident to functioning of said lost motion device during said period of dwell. 5
